FINISHING, DRAINING, AND PACKING
MECHANISM FOR CENTRIFUGAL CAST-
ING MACHINES

Marko T. Soso, Los Angeles, Calif.

Application September 30, 1933, Serial No. 691,657

8 Claims. (Cl. 25—30)

This invention relates to the casting of hollow objects from plastic material, such as of cement or concrete. The objects to be cast, may be pipe, posts or other hollow ware.

5 The usual process is to impart rapid rotation to a cylindrical mold, and to feed a wet mixture of the cement or concrete to the interior of the mold. Centrifugal force throws the plastic material to the walls of the mold. In order that 10 the material be distributed quite uniformly, and to pack it, it has been necessary to rotate the mold at high speeds, of the order of 400 revolutions per minute, and to make the mixture quite wet. However, at such speeds there is danger 15 that the heavier constituents, such as the rock or gravel aggregate, may be thrown out toward the outer periphery, providing a non-homogeneous product.

It is one of the objects of this invention to 20 make it possible to secure effective packing of the plastic material, although the speed be as low as 200 revolutions per minute, for pipe of about three feet internal diameter.

In order to improve the quality of the cast 25 product, it is necessary to remove the excess moisture, expressed from the plastic material. This moisture usually forms an overlying layer on the interior surface of the cast product. The removal of this excess moisture, such as by 30 brushing or otherwise acting on the surface of the product during or after the molding operation, has been attended with considerable difficulty.

It is thus another object of the invention to 35 make it possible to drain this excess moisture in a convenient and simple manner, and without the necessity of emptying receptacles used for collecting the moisture.

It is still another object of the invention to 40 provide a simple and inexpensive device for finishing or trowelling off the interior surface of the casting while it is plastic. This finishing off is important, because centrifugal castings are made in molds having only an exterior contact 45 wall for the casting, the interior surface of the casting being formed in response to the spreading action of centrifugal force. For this reason, slight irregularities are apt to occur on the 50 interior surface, which should be finished off for providing a good grade of product, free from surface porosities.

It is still another object of the invention to 55 provide a simple device that can accomplish simultaneously all three functions of draining

excess moisture, packing the plastic material, and finishing its interior surface.

This invention possesses many other advantages, and has other objects which will be readily apparent from a consideration of the embodiment of the invention shown in the drawing accompanying and forming part of the present specification. While a simple form arranged for manual operation has been shown, it will be evident to one skilled in the art, that the 60 finishing, draining, and packing device can be combined in various ways with other elements of existing machines; for example, it may be supported beneath or above a charging hopper which places the wet plastic material in the 65 revolving mold. The form shown will now be described in detail, illustrating the general principles of the invention; but it is to be understood that this detailed description is not to be taken in a limiting sense, since the scope of the 70 invention is best defined by the appended claims.

Referring to the drawing:

Figure 1 is a diagram showing the device in section, and in use within the interior of a pipe being molded;

Fig. 2 is a fragmentary sectional view taken along plane 2—2 of Fig. 1;

Fig. 3 is an enlarged detail section taken along the plane 3—3 of Fig. 1; and

Fig. 4 is a pictorial view of the apparatus.

In the present instance there is shown a centrifugal mold 1 of general cylindrical configuration and disposed on a horizontal axis. In order to rotate the mold at a rapid rate sufficient to utilize centrifugal force, a series of flanged rollers such as 2, 3 can serve to engage the circular band or track 4, disposed on the outside of the mold 1. It is to be understood, however, that a plurality of spaced tracks 4 may be used. Only one is shown in Fig. 2 since only one end 95 of the mold 1 is illustrated. The mold 1 may be of the order of three feet in diameter and may be eight feet or more in length.

By rotating one or more of the rollers 3 as by the aid of the shaft 5, the mold 1 is rotated 100 about its horizontal axis. Wet plastic material such as concrete or cement can be fed into the interior of the mold 1. Due to centrifugal action this plastic material is disposed to form an article 6, such as hollow pipe.

In the present instance the article 6 is shown as made for concrete and mold 1 can be rotated at the rate of about 200 revolutions per minute. After a definite thickness of material is deposited to form the article 6, it is necessary to finish 110

and pack the article, as well as to collect the excess mixture exuding from the plastic material.

In order to accomplish this result, the mold 1 is kept rotating after the article 6 is formed. There is inserted into the interior of the molded article a device which performs the finishing and packing function; and also preferably the function of draining the water from the interior 10 of the article 6. The finishing and packing is accomplished by contacting the interior surface of article 6 with a pair of members 7 and 8. These elements contact the interior surface and are spaced apart by a distance slightly less than 15 the interior diameter of article 6. In this way they contact at points which are at the extremities of a chord of the interior circle of article 6. For this purpose the elements 7 and 8 are supported in spaced relation and there is sufficient 20 weight in the device to hold these contacting members in the position shown in Fig. 1, below the horizontal diameter of the article 6.

In the present instance, these contacting members 7 and 8 are in the form of metal rollers 25 having axes parallel to the axis of mold 1. The structure for holding them in spaced relation is preferably in the form of a shallow receptacle 9. This receptacle 9 has a converging bottom 10 and end members 11 and 12 between which the 30 rollers 7 and 8 are journaled. The manner in which the bearings are provided for the rollers is shown to best advantage in Fig. 3. In that case it is seen that a roller bearing structure 13 has its outer race supported in an interior recess in roller 7; and the inner race is mounted on a shaft 14 passing through the rollers and held in place as by the internally threaded member 15. This internally threaded member 15 engages external threads on the extremity of shaft 14, and can have a flat head 16 35 with a kerf 17. The head 16 can be accommodated in an appropriate aperture in the end wall 11 or 12.

The receptacle 9 acts to collect moisture from 40 the interior wall of article 6 as the mold 1 is rotated. For this purpose the bottom 10 of the receptacle extends beneath each of the rollers 7 and 8. Thus when mold 1 is rotated in a 45 counterclockwise direction as indicated by arrow 18 of Fig. 1, roller 8 is also rotated in a counterclockwise direction and water from the interior surface of article 6 is captured on the outer periphery of roller 8 and is discharged into the receptacle 9. Some of the water may 50 accumulate beneath the line of contact between roller 8 and the interior surface of article 6. From this position it can flow into the collection receptacle 9, as indicated by the arrows 19.

Further excess moisture can be collected in a 55 similar manner by the action of roller 7. In this case the roller 7 is also rotated in a counterclockwise direction, the water collecting above the roller 7 and between the roller 7 and the inner surface of article 6 is thrown up against a 60 circular guard or shield 20. This shield reflects the water downwardly as indicated by the arrow 21 into the receptacle 9. There is sufficient weight imposed upon the receptacle 9 to keep 65 rollers 7 and 8 in relatively horizontal position; and this weight also acts to impart a packing action through the intermediary of the rollers 7 and 8 on the inside of article 6.

It is apparent that the device including the 70 receptacle 9 and the rollers 7 and 8 is supported at the points of contact between the rollers 7 and

8 and the interior of article 6. In this way the rollers act as smoothers and trowellers to finish the interior surface and to reduce porosity and irregularities in it.

The insertion of the device is simple. It can be done by hand, as by merely lifting it into the article 6 and letting it rest by gravity in the position shown. When so placed inside the article 6, it can be manipulated by hand to traverse the whole length of the article 6. Several back and forth motions may be necessary to secure a fully finished and packed product.

In order to drain the collected moisture from receptacle 9, a drain pipe 22 can be provided leading at a downward slant from the bottom 10 of the receptacle 9 to the exterior of the mold 1. Thus pipe 22 can have a slot cut in it immediately below the receptacle 9 and in registry with a draining aperture 23 in the bottom 10. The pipe 22 can have a downwardly directed extension 24 which may effectively serve as a handle for manipulating the device in its back and forth travel inside of article 6. If desired, another handle member 25 (Fig. 2) can be coupled to the inner end of the receptacle 9 so that it 100 may be manipulated from the other end of the mold 1.

It is of course to be understood that the device including receptacle 9 and rollers 7 and 8 can be readily removed by hand from the article 105 6 whenever the operations of draining, finishing and packing are completed. When this is done, the rotation of mold 1 can be stopped and the article 6 removed therefrom. Upon use of the device as described, it is possible to pack the 110 plastic material very effectively and to collect the excess moisture in a simple and rapid manner. This can also be accomplished at a comparatively low rate of rotation for a mold 1.

I claim:

1. In a device for operating upon the interior surface of a hollow cylindrical article cast centrifugally from plastic material, the axis of said article being non-vertical, a pair of surface contacting means, and a support for spacing said means at a distance such that the surface contacting means rest by gravity below the interior diameter of the article, and upon the interior surface thereof.

2. In a device for operating upon the interior surface of a hollow cylindrical article cast centrifugally from plastic material, the axis of said article being non-vertical, a pair of rollers arranged to contact the interior surface of the article, and a support for spacing said rollers to permit them to rest by gravity below the interior diameter of the article, and upon the interior surface thereof.

3. In a device for operating upon the interior surface of a hollow cylindrical article cast centrifugally from plastic material, the axis of said article being non-vertical, a moisture collecting receptacle adapted to be inserted in the article and to be supported thereby before it has set and during rotation thereof, and a pair of surface contacting means spaced on said receptacle for contacting with the interior surface of the article.

4. In a device for operating upon the interior surface of a hollow cylindrical article cast centrifugally from plastic material, the axis of said article being non-vertical, a moisture collecting receptacle adapted to be inserted in the article before it has set and during rotation thereof, and a pair of parallel rollers spaced on said recep-

tacle for contacting with the interior surface of the article, and for supporting said receptacle therein.

5. In a device for operating upon the interior surface of a hollow cylindrical article cast centrifugally from plastic material, the axis of said article being non-vertical, a moisture collecting receptacle adapted to be inserted in the article before it has set and during rotation thereof, a 10 pair of surface contacting means spaced on said receptacle for contacting with the interior surface of the article, and for supporting said receptacle therein, and a drain leading from the receptacle to the exterior of the article.

15 6. In a device for operating upon the interior surface of a hollow cylindrical article cast centrifugally from plastic material, a moisture collecting receptacle adapted to be inserted in the article before it has set and during rotation thereof, a 20 pair of surface contacting means

spaced on said receptacle for contacting with the interior surface of the article, and a shield above one of the surface contacting means for guiding the water expressed by said means into the receptacle.

7. In a device of the character described, a receptacle, and a pair of parallel finishing and packing rollers arranged on opposite sides of the receptacle, and above the bottom thereof, for causing the receptacle to collect moisture expressed by the rollers.

8. In a device of the character described, a receptacle, a pair of parallel finishing and packing rollers arranged on opposite sides of the receptacle, and above the bottom thereof, for causing the receptacle to collect moisture expressed by the rollers, and a drain pipe leading from the bottom of the receptacle.
